CANISTER UNIT WITH LATCHING MEANS
James A. Donlevy, Burlington, N.C., assignor, by mesne assignments, to the United States of America as represented by the Secretary of the Air Force
Filed Sept. 19, 1961, Ser. No. 139,316
4 Claims. (Cl. 339—91)

This invention relates to electrical equipment of the type wherein a multiplicity of electrical elements are packaged into a canister and are then connected to an electrical apparatus by means of multiple pins which enter and make sliding engagement with suitable sockets in a mounting pad.

It is well known that in mobile applications such as space vehicles and especially in applications where canisters are subjected to vibration, shock, centrifugal and other forces, difficulty is experienced in maintaining firm mechanical and electrical contact of the canistered elements which for the purposes of this application include electrical components, electro-mechanical components and printed circuits.

In order to assure firm mechanical and electrical reliability of canistered electrical elements used in severe applications, it is customary to latch the canisters in place.

Latching devices used in the past to maintain firm mechanical and electrical connection have been of complex design and have not been completely satisfactory for the severe conditions encountered on space vehicles. Such latching devices have greatly added to the overall physical size of the canisters to which attached, thereby increasing the minimum spacing between adjacent canisters with a resulting increase in the overall physical size and weight of the electrical apparatus to which attached.

The primary object of this invention is to provide a simple fail-resistant latch which will not increase the minimum spacing between adjacent canisters and which will withstand the environment encountered in space flight.

Another object of this invention is to incorporate a handle on each canister for its removal and for operation of the latching device.

More objects of novelty and utility will be apparent from the following description and drawings in which like parts are designated by like numerals:

FIG. 1 is a perspective elevation of the canister with operating handle in the home position;

FIG. 2 is a sectional side elevation along line 2—2 of FIG. 1 with the operating handle in the home position;

FIG. 3 is a sectional side elevation on the same plane as FIG. 2 showing the canister mounted and latched to the electrical apparatus;

FIG. 4 is a perspective of the guide can, partially broken to show installation of a latch spring;

FIG. 5 is an exploded perspective sectional elevation showing relationship of parts and with a latch spring unlatched;

FIG. 6 is a partial perspective elevation of another embodiment of the invention showing the handle lock spring in the locked position;

FIG. 7 is a partial perspective elevation along line 7—7 of FIG. 6 partially broken to show the operation of the lock spring;

FIG. 8 is a partial perspective of operating handle end showing construction details;

FIG. 9 is a partial perspective elevation of a canister showing T-slot and lock spring detents;

FIG. 10 is a partial side elevation showing the canister in the latched position and the lock spring in the release position; and

FIG. 11 is a partial perspective of a guide can showing

2

the lock spring relief and hole for nesting the latch spring.

Referring to FIG. 1 and FIG. 5 the preferred embodiment of the invention is shown in connection with a housing or canister 10 designed to encapsulate one or more electrical elements such as relays or printed circuits which elements are then mechanically and electrically connected into an electrical system by means of terminal pins

12 which engage suitable sockets 14 in a mounting pad 16 which is located within guide can 18 as shown in FIG. 4. The electrical elements encapsulated within housing 10, the manner of connecting the electrical elements into the electrical system and the manner of guiding housing 10 by means of the guide can 18 are all well known to the art and form no part of this invention. Mounting pad 16 and guide can 18 which is shaped in the form of an open box are mounted to panel member 20 of an electrical apparatus by any suitable means known to the art and forms no part of this invention.

10 Opposing side walls of canister 10 have T slots 22 as shown in FIG. 5 which are milled or otherwise formed along the longitudinal center lines and which slideably guide and restrain operating handle 24 in a manner to be hereinafter described.

15 20 25 Operating handle 24 is formed to substantially the shape depicted to provide a U-shaped structure with opposing side members 26 which are parallel and slideably operate in T slots 22 of canister 10. The operating handle 24 is preferably formed from flat spring stock such as stainless steel or Phosphor bronze in order to maintain structural rigidity in operation.

Both edges of each side member 26 of operating handle 24 have a relief 28 which limits the movement of the operating handle by engagement with pin 30 which is staked or otherwise joined to canister 10. Each side member 26 terminates in spear shaped ends 32 with cam surfaces 32a which engage and operate latch spring 34 in a manner to be hereinafter described.

20 25 30 35 FIG. 4 depicts only one latch spring 34, the spring on the opposite end within guide can 18 having been omitted for clarity. Latch spring 34 is formed to substantially the shape depicted and is in its free position. The bottom of guide can 18 has a hole 36 for each spring, the hole being of such size and shape as to provide a nest for the bent loop portion of the latch spring. The upright portion 38 of the latch spring is disposed between the end of mounting pad 16 and the inside of guide can 18 and in such lateral relationship as to permit entry into T slot 22 of canister 10 when the canister is introduced into the guide can. The bent loop portion of latch spring 34 is retained in hole 36 of guide can 18 by means of the mounting pad 16. It is thus seen that after the guide can 18 and mounting pad 16 are mounted to panel member 20 of an apparatus, the latch spring 34 is firmly located and retained in its nesting hole 36.

30 35 40 FIG. 3 depicts the canister 10 in its home position and latched in place, the spear shaped end 32 of operating handle 24 having spread the upright portions 38 of latch spring 34, thereby forcing latch spring ends 34a into mating holes 40 in canister 10. It is thus seen that canister 10 will remain firmly joined to the apparatus, being retained in place by the latch spring ends 34a engaging holes 40 in canister 10.

45 50 55 60 65 In operation, the canister may be disconnected from the apparatus by lifting up on operating handle 24 which will disengage the spear shaped end 32 from latch spring 34 to permit latch spring ends 34a to disengage from holes 40 in canister 10. Further lifting of the operating handle after edge 28b of relief 28 engages pin 30 will pull the canister from guide can 18.

The canister may be connected to the apparatus and

latched in place by guiding the canister into the guide can 18 while the operating handle is in its extended position and then pushing the operating handle home until edge 28a of relief 28 engages pin 30, thereby spreading latch spring 34 and forcing latch spring ends 34a into holes 40 in canister 10.

FIG. 6 through FIG. 11 depicts the addition of an operating handle lock spring to the preferred embodiment of the invention. This lock spring permits driving the canister to its home position by applying force only to the handle 64. Canister 60 is identical with previously described canister 10 except for the addition of detents 62 cut into the side of T slots 22 as shown in FIG. 9. Operating handle 64 is identical with previously described handle 24 except for the addition of rectangular holes 66 as shown in FIG. 8. Guide can 68 is identical with previously described guide can 18 except for the addition of relief 70 as shown in FIG. 11. Relief 70 is of a width not to exceed the width of the leg of the T slot 22 in canister 60 and at its outer extremity terminates in beveled edges 70a and 70b which act as cam surfaces for disengaging lock spring 72 from detents 62 when installing and latching the canister in its home position.

Handle lock spring 72 is formed to substantially the shape depicted in FIG. 6 and FIG. 7 and is formed from spring wire of a diameter not to exceed the metal thickness of operating handle 64. The loop portion of lock spring 72 is of such size and form as to nest within hole 66 in operating handle 64. The free ends of spring 72 are at substantially 90° to the loop portion of the spring and are slightly longer than the thickness of web 22a of T slot 22 and biased to spring into detents 62 of the T slot.

It is thus seen that when operating handle 64 is in its extended position and lock spring 72 is in engagement with detents 62, the operating handle cannot be moved independently from canister 60.

The operating handle 64 is held in its extended position by the engagement of lock spring 72 with detents 62 in canister 60. When the canister is inserted into guide can 68, the lock spring will be released by the cam action of the beveled edges 70a and 70b on the guide can. The lock spring is now ineffective and will remain so until the handle is pulled upward with intent to remove the canister from the guide can. At this time the lock spring will reengage the detents in the canister and lock the handle in the "up" position. This locking feature facilitates installation of units which are closely spaced to each other.

While the embodiments of this invention disclosed by the specification and drawings are in connection with electrical elements packaged into a housing or canister, it is obvious that the invention may be used with elements not packaged or mounted in this specific manner.

What is claimed is:

1. A device for connecting and disconnecting canister enclosed electrical elements having multiple pin connectors to and from a mounting pad of an electrical apparatus and latching same in place comprising in combination a metal housing member enclosing said electrical elements and having T slot channels in two opposing side walls which are substantially flat and parallel, a guide member for guiding said housing member onto said mount-

ing pad, said guide member being open box shaped and spaceably encompassing said mounting pad, spring latching means disposed between said mounting pad and said guide member, said spring latching means having spreadable upright portions for entry into the T slots of said housing member, means in the form of a U-shaped handle slideably operating with limited motion in the T slots of said housing member for connecting and disconnecting said housing member from said mounting pad, said handle terminating in means for actuating said latching means, said actuating means comprising spear shaped cams to spread said upright portions of said latching means to force ends of said latching means into corresponding holes in said housing member to latch said housing member after connecting to said mounting pad and to unlatch said spring latching means before disconnecting said housing member from said mounting pad.

2. A device for connecting and disconnecting canister enclosed electrical elements having multiple pin connectors to and from a mounting pad of an electrical apparatus and latching same in place comprising in combination a metal housing member enclosing said electrical elements and having T slot channels in two opposing side walls which are substantially flat and parallel, a guide member for guiding said housing member onto said mounting pad, said guide member being open box shaped and spaceably encompassing said mounting pad, spring latching means disposed between said mounting pad and said guide member, said spring latching means having spreadable upright portions for entry into the T slots of said housing member, means in the form of a U-shaped handle slideably operating with limited motion in T slots of said housing member for connecting and disconnecting said housing member from said mounting pad, said handle terminating in means for actuating said latching means, said actuating means comprising spear shaped cams to spread said upright portions of said latching means to force ends of said latching means into corresponding holes in said housing member to latch said housing member after connecting to said mounting pad and to unlatch said spring latching means before disconnecting said housing member from said mounting pad, said handle terminating in means for actuating said latching means, said actuating means comprising spear shaped cams to spread said upright portions of said latching means to force ends of said latching means into corresponding holes in said housing member to latch said housing member after connecting to said mounting pad and to unlatch said spring latching means before disconnecting said housing member from said mounting pad, and means for locking and unlocking said handle to said housing member when said handle is in the extended position.

3. A device in accordance with claim 2 in which said means for locking and unlocking said handle consists of a spring.

4. A device in accordance with claim 2 in which said means for locking and unlocking said handle consists of a spring for locking and unlocking said handle to and from said housing member, said spring nesting within a side member of and traveling with said handle.
